L. MORABITO

GAS BURNER FOR HEATING PURPOSES

Filed Sept. 29, 1926

Patented July 19, 1927.

1,636,643

UNITED STATES PATENT OFFICE.

LUIGI MORABITO, OF PORT CHESTER, NEW YORK.

GAS BURNER FOR HEATING PURPOSES.

Application filed September 29, 1926. Serial No. 138,441.

This invention relates to gas burners for heating purposes and has for its object to provide, in a manner as hereinafter set forth, a burner of such type which when used will provide for efficient and expeditious heating of a stove, range, boiler and furnace, with which it is employed, as well as further providing for heat radiation from the outer end thereof to assist in the heating operation.

Further objects of the invention are to provide, in a manner as hereinafter set forth, a gas burner for heating purposes, which is simple in its construction and arrangement, strong, durable, compact, thoroughly efficient in its use, conveniently installed, capable of being constructed of any size and to be used in various types of stoves, boilers or furnaces employed for heating purposes, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is an elevation of a gas burner in accordance with this invention.

Figure 2 is a cross section thereof intermediate its ends.

The burner which is of any suitable length and diameter is referred to generally by the reference character 1 and is constructed of any suitable material, preferably cast iron. The burner comprises a tubular body portion 2, a head 3 and a base 4. The head 3 is solid and of greater diameter than the base 4. The body portion 2 is of less diameter than the base 4 and is formed integral with the head 3 and base 4. The head 3 is rounded and the body portion 2, at its point of joinder with the head 3 is flared as indicated at 5. The diameter of the body portion 1, that is to say the outer diameter thereof is preferably three inches and the thickness of the body portion 2 preferably is one half inch. It is to be understood that the diameter of the body portion, as well as

its thickness can be as desired. The head 3 of the burner is provided for heat radiating purposes. The base 4 is adapted to be coupled with a gas supply and for such purpose the base 4 is formed with a depending nipple 6 for connection with a feed or gas supply pipe, not shown. The nipple 6 is axially disposed with respect to the lower face of the base 4, and the latter is provided with a concave chamber 7 into which the nipple 6 communicates. The body portion 2 is integral with the upper face of the base 4 and the chamber 7 opens into the lower end of said body portion 2.

The body portion 2 is formed with superposed rows of circumferentially extending spaced openings. The rows are equally spaced with respect to each other and the openings of the rows align with each other. The openings of each row are radially disposed and are indicated at 8. The lowermost row of openings is spaced in close proximity to the lower end of the body portion 2, but the uppermost row of said rows of openings is spaced a greater distance from the head 3 than the distance between the lowermost row and the base 4. The upper terminal portion of the body portion 2, which is indicated at 9 is not provided with the openings 8 or in other words it is not perforated. Preferably the number of openings 8 of each row is sixteen and are equally spaced. The rows of openings provide for the passage of the gas, in the form of jets, and which are ignited.

The construction of the burner provides for a thoroughly efficient and expeditious heating when the burner is employed in connection with a stove, range, furnace or boiler and with the flames radiating with respect to the body portion of the burner. Furthermore the construction of the burner provides for the radiation of heat from the upper end thereof which facilitates the heating operation. Therefore it is thought the many advantages of a gas burner for heating purposes, in accordance with this invention, can be readily understood, and although the preferred embodiment of the invention is as illustrated and described, yet it is to be understood that changes in the details of construction can be had which will fall within the scope of the invention as claimed.

What I claim is:

1. A gas burner comprising a tubular body portion provided with spaced rows of cir-

5 circumferentially extending openings, a solid, heat radiating head integral with one end of said body portion and of greater diameter than the latter, and a chambered base of greater diameter than and integral with the other end of said body portion, the chamber of the base opening into the body portion, and said base having a nipple extended therefrom adapted to couple a gas supply pipe 10 therewith.

15 2. A gas burner comprising an apertured tubular body portion, a chambered base at one end thereof and having means for connection with a gas supply, and a solid heat radiating head integral with and closing the other end of the body portion, of greater diameter and thickness than that of said body portion and of greater diameter than that of the base.

20 3. A gas burner comprising a tubular body portion provided with spaced rows of circumferentially extending openings, an annular, solid heat radiating head integral with one end of said body portion, said head

25 extended from the body portion and of greater diameter than the diameter of the latter, a base provided with a chamber opening into the other end of said body portion, the said other end of said body portion integral with the base, and an intake nipple 30 arranged centrally of the lower face of the base and opening into the chamber of the latter, said base of greater diameter than the diameter of said body portion and of less diameter than the diameter of said head. 35

4. A gas burner comprising a tubular body provided with circumferentially extending spaced rows of openings, said body having a flaring upper end, a base integral with the other end of said body, projecting laterally therefrom and provided with a chamber opening into said body and adapted to communicate with a gas supply, and a circular, solid, heat radiating head integral with and closing the flared upper end of said body 40 and of materially greater diameter and thickness than that of said body.

LUIGI MÓRABITO.
